UNITED STATES PATENT OFFICE.

LOUIS LÉON BILLANT, OF PARIS, FRANCE.

HAND-GRENADE.

1,217,556.

Specification of Letters Patent.

Patented Feb. 27, 1917.

Application filed April 18, 1916. Serial No. 91,962.

To all whom it may concern:

Be it known that I, LOUIS LÉON BILLANT, a citizen of the French Republic, and residing at Paris, in France, have invented certain new and useful Improvements in Hand-Grenades, of which the following is a full, clear, and exact description.

This invention has for its object to provide an improved percussive hand grenade having an automatic stabilizer and disengagement acting upon release.

A plurality of constructional forms of said grenade are illustrated in the accompanying drawings in which:

15 Figure 1 is a section of one constructional form, showing the explosive, the detonator and the percussion pin.

Fig. 2 illustrates the percussion pin and the safety device in detail.

20 Fig. 3 shows the complete grenade provided with the safety device in its effective position.

25 Figs. 4 and 5 show a modification of arrangement of the wings or empennage, the raising of which is effected automatically under the action of a spring, in the armed position.

30 Referring to Figs. 1 to 3, the grenade comprises a casing (a) adapted to contain powder and shrapnel bullets, the shape of which is such that it presents a preponderance of weight toward the nose (b) and as small a weight as possible at the upper or tail part; the stabilization is completed by 35 a kind of tail which may be formed by a string (k) with or without a mass of any shape at the end, a ribbon or the like, even a tail of rigid and light material (for instance wood) or any other material, may be provided; this tail may also be used as a means for throwing the grenade.

35 The percussion system may be mainly constituted either by a primed detonator (c) or by a simple detonator with a primer, located 40 and tightly driven into a tube (d); or else by a percussion pin connected with a small mass or pellet (e) sliding in the tube (d) and in a nut (g) screwed upon the upper part of the grenade (a), the travel of said 45 pin being limited by a pin (f) passing through a slot (f') formed in the mass, or other similar means. A shock-absorbing spring (r) avoiding detonation upon a slight shock, is located between the detonator and 50 the small mass or pellet. The whole of the system may be inverted: the percussion pin

may be stationary and the detonator be connected to the small mass or pellet.

The safety system is constituted by a safety cam (h) with a lever (i) pivoting at 60 (j) on the top of the head of the pellet and maintaining the same rigidly at the top of its stroke when the lever (i) is folded back against the body of the grenade (Fig. 3). The disengagement of the said eccentric is 65 obtained upon launching by the resistance to air by the tail (k) of the grenade (string or ribbon) secured to the end of the lever (i). The string (k) is connected to a cap or casing (l) with which the grenade and the 70 safety device are covered, for instance, for transporting purposes; Fig. 3 shows this arrangement.

In the construction illustrated in Figs. 4 and 5, the arm (i) is replaced by a metallic 75 member (i') forming a cap, with one or two safety cams (i''), which is extended in the form of a spoon to bear against the body of the grenade (non-operative position shown in full lines) and which is maintained on 80 the grenade by a closure seal (m) combined with a string (n). The tail (o) of the wing arrangement or empennage is formed by a ribbon attached at (o') and terminated by a ballast or weight (p), the whole being 85 located in the spoon and applied to the body of the grenade in the position of rest.

Fig. 4 shows the position of the member (i') in dotted lines when the grenade is 90 armed or operative, a position which is obtained automatically when the closure seal has been broken, by means of a coiled spring (r) wound upon the axis of rotation of the empennage (i') between the branches of the head of the pellet (e); this spring bears on 95 the one end in the interior of the member (i') and, on the other, on a cross pin (s) secured to the upper part of the pellet.

After launching, the whole of the empennage and of the ribbon tail stabilize the 100 grenade and guide the same upon its path in such a manner that it moves with the base of its pear-shaped portion forward, and the percussion of the pellet takes place effectively when the grenade comes into contact with an obstacle, producing the explosion of the grenade.

Having fully described my invention, what I claim as new and desire to secure by 110 Letters Patent is:

A hand grenade of the character described comprising in combination with a pear-

shaped casing containing the explosive, and a percussion system, a safety system comprising a safety cam adapted to hold the percussion system inactive when the grenade is
5 not to be used, means connected to said cam for launching the grenade, a tail or empennage, a seal for maintaining said tail in its inoperative position, and a spring for rais-

ing said tail upon the rupture of said seal, substantially as described.

In testimony whereof I affix my signature in presence of two witnesses.

LOUIS LÉON BILLANT.

Witnesses:
